BUILDING STRUCTURE AND METHOD OF
MAKING SAME

George L. Dresser, Albany, N. Y.

Application July 27, 1931, Serial No. 553,449

19 Claims. (Cl. 20—7)

This invention relates to building structures and methods of making the same.

The present application is a continuation in part of my copending application Serial No. 486,5840, filed October 6, 1930.

It has heretofore been suggested that building structures, such, for instance, as a floor, may be formed or built up by securing an upper layer of blocks or panels to a base or sub-floor by means of an adhesive substance or binder. Numerous floors have been laid in this way, particularly where it has been desired to have a floor comprising an ornamental and serviceable wearing surface of hard wooden blocks, arranged in an attractive manner, mounted on a firm and solid base of wood or concrete. Very considerable difficulties have been met with, however, in the construction of such floors, particularly in applying the upper layer of blocks to the sub-floor. Generally the blocks have been applied singly, each being coated, on its under side at least, with an adhesive or binding substance, just prior to being finally positioned. This has been a comparatively expensive procedure as well as a time consuming one, and the completed floor has oftentimes shown irregularities of block alignment and surface which detract from its appearance and serviceability.

The present invention has for its general object the provision of an improved method of laying floors, or building up similar structures, by which a layer of blocks, panels, or other units can be secured in position on a base or support quickly, conveniently and economically. Furthermore, by the practice of the improved method, a floor or other built-up structure of highest quality is obtained, the provision of which comprises another object of the invention. The invention is particularly adapted to be practiced in the laying of floors and will be disclosed as employed in the laying of a floor with a concrete base and upper layer of hardwood blocks, by way of example, but it will be understood that it may be profitably practiced in the construction of paneled walls and ceilings and in the fabrication of other structures.

Generally speaking, the method, as practiced in the laying of a floor, consists in first applying an adhesive or binding surface to the sub-floor, preferably as a continuous coating over the upper surface of the sub-floor, then emplacing the sections of the upper surface in position on the sub-floor, and in finally softening the adhesive or binding substance so that the softened adhesive is caused to make intimate contact with

the lower surfaces of the blocks, which together constitute the upper floor surface, and the upper surface of the sub-floor. When this adhesive is allowed to cool and harden, the several blocks are firmly secured to the sub-floor and in the positions which they are intended to finally occupy in the completed floor.

I may apply the adhesive or binding substance to the sub-floor as a viscous liquid or semi-solid to form a continuous coating over the sub-floor and apply, in addition to this binding substance, a wire screen to the sub-floor through which a current of electricity may be passed after the upper surfacing of blocks is laid, so that the binding material is softened by the heat evolved from this wire screen, which acts as an electrical resistance element. Alternatively, I may add the binder to the wire screen at a point remote from that where the floor is to be laid, or the binder may be applied to the blocks themselves at a remote point, allowed to dry, and the binder coated blocks used at the point where the floor is being constructed, the blocks being laid directly upon a metallic resistance element of suitable character.

Finally, I prefer to quickly roll the upper surface of the nearly completed floor, that is, roll this surface while the binder is still soft, with the end in view of causing the lower surfaces of the individual blocks to intimately contact with the binder and to insure that the upper surfaces of these blocks lie in the same horizontal plane. It will be obvious to those skilled in the art, however, that the various steps of the novel method may be changed considerably to suit different operating conditions.

As the electrical resistance element is left in place permanently intermediate the upper layer of flooring blocks and the sub-floor, it is obvious that, where the proper type of binder is employed, the floor may be subsequently disassembled by reversing the steps of assembly, i. e., by passing an electric current through the resistance element and, when the heat evolved has been sufficient to soften the binder, to then remove the individual blocks which together make up the upper surface.

A further object of the invention is to provide improved types of flooring block from which the upper surface of a built-up floor of this general type may be constructed.

Still further objects of the invention are to provide easily accessible means for effecting the electrical connections necessary in the carrying out of the process described, and to provide

means for equalizing the flow of current through the resistance element in the vicinity of the cut away portions of the applied flooring, such, for example, as occur at the base of columns or partitions, or at similar interruptions in the continuity of the floor.

Referring now to the accompanying drawings. In Figure 1 a corner portion of a floor constructed in accordance with the principles of my invention is illustrated in plan, partly broken away to show the sub-floor and the intermediate binding substance and resistance element;

Figure 2 is a vertical cross sectional view taken on the line 2—2 of Fig. 1;

Figure 3 is a vertical cross section on an enlarged scale through an intermediate portion of the flooring at a point between two of the strips of resistance material;

Figures 4, 5 and 6 illustrate in perspective alternative forms of blocks or floor units adapted to be employed;

Figure 7 is a diagrammatic view of the electrical apparatus and material employed in carrying out my improved method;

Figure 8 is an enlarged sectional view illustrating the relative thicknesses of the various layers making up the floor, before the resistance element has been pressed into the binder;

Figure 9 is a fragmentary, partially diagrammatic plan view of an arrangement whereby the heating current is equalized at portions of the flooring where the resistance element is interrupted; and

Figure 10 is a view in vertical cross section taken on line 10—10 of Fig. 9.

The sub-floor is indicated at 10, and this may be of any chosen construction. In the drawings it is illustrated as being of concrete, but the invention is in nowise limited to the use of any particular materials. The upper surface of the sub-floor should be clean and smooth and should be of such character that the binding material used will adhere thereto. The blocks 11 which together go to form the top or wearing surface of the floor are preferably elongated, as shown in the drawings, and are preferably of wood or composition, but here again it will be understood that the blocks may be of any desired shape and any material which may be suitable as flooring material and to which a binder will adhere.

In the laying of the applied flooring (after the sub-floor has been completed) and in accordance with one method of practicing the novel process, the first step is to apply the adhesive or binding substance to the upper surface of the sub-floor. Although, within the purview of the invention in its broader aspects any suitable or desired substance may be employed in this connection, it is preferred to use an asphalt having a melting point of about 155° F. and a penetration of 40 at 72° F. Asphalts of lower or higher melting points than this preferred example may be employed, and it will be understood that the present invention may be advantageously applied in any case wherein the adhesive or binding substance is a solid at ordinary temperatures and whose melting or fusing point is preferably not much over 200° F. which has been found to be the most suitable and economical temperature to be attained by the heating unit with readily available electrical equipment. In special cases, of course, this temperature may be exceeded if necessary and if the proper equipment is at hand.

The binder layer designated 12 in the draw-

ings is applied to the sub-floor 10 preferably in a soft or liquid state and of the approximate thickness of one eighth of an inch. A strip of electrical resistance material 15 is then laid on the layer of binder preferably while the material is still soft, although it may, if desired, be applied after the binder substance has set. Although for differing installations the resistance element may be modified and assume various forms and dimensions, experiment thus far has shown that in the preferred example of the application of my invention, the resistance element should take the form of strips of wire screen of about 20 gauge and having a mesh of three quarters of an inch or one inch in diameter, the interstices being preferably hexagonal. The thickness of the resistance element will be about one sixteenth of an inch so that it may readily be embedded in the layer of binder material and still permit the binder to expand or overflow into the grooves of the blocks, as will be described later. Also, as will be later explained, the strips of resistance material are preferably three feet wide and each about eighty feet in length. After being laid upon the layer of binding material the strips may be rolled lightly to secure a slight initial penetration of the resistance element in the binder material. Although the resistance element may be fabricated in various ways, it should be so designed that, when an electrical current is passed through the element and heat developed, the heat can readily reach and soften substantially all of the binding material. In other words, the various members of the screen or resistance element should not be spaced too far apart for the purpose intended.

The blocks 11 are then laid up or positioned in any suitable attractive design upon the level or approximately level surface provided by the binder substance and resistance material whereupon they are aligned and tightened in the positions that they are finally intended to assume in the completed floor. The resistance element strips 15 are provided at their ends with clamps or conductor bars 16 to which suitable wires or cables may be applied to connect the resistance elements with a suitable source of current, the current being of such magnitude that the resistance element is caused to evolve sufficient heat to cause the binder or adhesive to soften, become plastic and flow into intimate contact with the upper surface of the sub-floor and the lower surfaces of the individual blocks. With the apparatus to be described, this heating period will be about ten minutes in duration. Then, when the binding material is liquefied, the top surfaces of the blocks may be pressed or rolled to make certain that the lower surfaces have proper contact with the adhesive or binding substance and with the resistance element 15 and that the upper surfaces of the blocks lie substantially in the same plane. The roller, shown at 18 in Figure 2, should be of sufficient weight not only to secure the blocks in intimate contact with the binder, but also to force a portion of the binder into all openings or gaps provided in the blocks but not of such weight as to force the binding material to the upper surface of the blocks. During the rolling process the current may be gradually reduced until it is completely shut off but the rolling should continue until the binder substance has cooled and set.

The rolling or pressing operation naturally brings the lower surfaces of the several blocks into intimate contact with the resistance ele-

ment or screen, and, if the pressure applied is sufficiently great and the blocks are of wood, which is generally the case, the wires of the screen will be pressed slightly into the lower faces of the blocks, forming indentations due to the relative softness of the blocks. This screen therefore performs a dual function inasmuch as it constitutes a friction creating or "anti-skid" surface for the blocks both while the floor is being constructed and after it has been completed. In the average case the floor blocks are not submitted to a very heavy lateral pressure, but in certain instances, as where the block flooring is used in factories and there is a great deal of traffic in one direction, this anchoring function of the resistance element is of material benefit.

It has been found, that for most purposes, this novel method of laying flooring provides such an even upper surface that no further finishing thereof is necessary; however, for more elaborate or refined installations, the flooring may be finished off in any suitable manner, as by sanding, filling with paraffin or other waxes, varnishing or shellacking.

As has been explained before, the blocks may be subsequently removed in a very convenient manner by again passing a current through the resistance element and effecting the softening of the binding material. This is helpful in all cases where it is found necessary to occasionally replace the floor.

As indicated heretofore, the blocks, panels, or other surface material which is to be applied to a sub-floor, wall, or other support or base may be constructed of any desired or suitable material and in any shape applicable to the structure contemplated. For flooring purposes such as described in the exemplary embodiment of the invention in this specification, it is preferred to employ blocks constructed of wood or a similar material and which may take the forms illustrated in Figures 4, 5 and 6 of the drawings. In Figure 4, there is shown a wooden block which is adapted for general factory flooring construction and which may be modified by increasing the thickness thereof and having the grain extend vertically for heavy duty purposes. This block, designated 11a, is preferably rectangular in plan and the upper portion 20 thereof has the shape of a parallelepiped. The lower portion 21 thereof is provided with downwardly converging walls which give this portion the form of an inverted truncated pyramid. A series of grooves 22 are provided in the lower surface of the blocks and these grooves, together with the wedge-shaped gaps 23 provided between the lower portions of adjoining blocks, as clearly shown in Figure 3 of the drawings, provide spaces into which the softened binding material may flow during the application of the flooring so as to firmly unite the blocks to each other and to the base 10.

In Figure 5 a slightly modified block 11b is shown which is particularly adapted for use in houses and offices. The lower portion is constructed in a similar manner to that just described in connection with the block 11a but the upper portion is provided with longitudinal locking grooves 24 whereby adjoining blocks may be keyed together.

A further variation 11c is illustrated in Figure 6 of the drawings. This block is provided with parallel top and bottom surfaces, cylindrically curved side surfaces, one being a convex surface (at the rear of said block) and the other a concave

surface, indicated at 26, and cylindrically curved end surfaces, one of these surfaces 27 being convex and the opposite end surface being concave. In addition, the side and end surfaces of the blocks are provided with horizontal and vertical spacing lugs indicated respectively at 28 and 29, which project laterally and insure that equal spaces are left between the various blocks when the upper floor section is assembled. This block is also provided with longitudinal grooves 22 in its bottom surface, these grooves, as previously mentioned, constituting reservoirs for excess quantities of binder material which may be forced upwardly during the rolling of the applied flooring.

In laying a floor such as has been described, expansion spaces such as indicated at 30 in Figures 1 and 2 should be permitted to remain between the main body of the flooring and the walls 31 of the building. If desired, a single line of blocks 32 may be laid against the wall 31 and the spaces 30 bridged over by suitable gratings or cover plates 33, which plates may be secured in position as by means of the screws 34. As shown in Figure 3, similar openings 35 may be provided between the adjacent areas of the applied flooring which are underlaid by different strips of resistance material 15. A cover plate 36 may be used in this case which is adapted to be seated in suitable recesses or depressions 37 provided in the end blocks of the adjoining areas. The recesses 37 are slightly larger than the plate 36 so as to provide room for expansion. Screws 38 may be used to secure the cover plate in position along one side of the opening 35. These 105 spaces or openings 30 and 35, besides providing expansion means, may also provide ducts for electrical wiring, pipes or the like and are also designed to provide access to the ends of the strips of resistance material 15 for the attachment of conductors leading to the source of electrical current.

In Figure 7, there is illustrated diagrammatically one form of apparatus for generating, controlling, and applying the heating current to the 120 resistance strips 15. This suggested or preferred arrangement involves the use of a portable 75 kilowatt motor generator set, the motor being indicated at M and being connected to a current main 40 as by means of a switch S. An alternating current single phase generator G is operatively connected with the motor M and is provided with an exciter 41. A volt meter and ammeter are installed in the output line as indicated. Suitable switches S' and S² may be employed in line 42 connecting the generator with the transformer T. The transformer T is provided for stepping down the voltage to suit the wire resistance element requirements and is provided with means such as indicated at 43 for 130 adjusting the voltage output. Cables 45 lead from the transformer T to the resistance element 15 and are attached thereto by suitable connections with the clamps or end strips 16.

As the result of experiments, it was determined 140 that the current required was proportional to the width of the strips and the voltage necessary is proportional to the length thereof, and in the preferred form of apparatus in which 20 gauge wire is used and the screens are of three 145 quarter inch mesh, it was found that 200 amperes of current were required per foot of width and about one volt of potential per foot of length. Therefore, since the portable generator units available seldom have an output of over 700 am- 150

peres at 150 volts, the strips used should be about three feet wide by 150 or 160 feet in length. For most installations, however, it will be found more convenient to provide a plurality of strips, the total length of which is about 150 or 160 feet as, for example, where two strips 15 are employed as in Figure 7, they will be three feet wide and each about eighty feet in length. It will be readily understood that the invention is in no wise limited to apparatus or material of these dimensions and characteristics since any size of strip and strength of current may be used compatible with the conditions attending the particular installation. If, for example, suitable power lines are available the generator may be eliminated and strips of a width of five or six feet may be employed, the current used in this case being about 1000 to 1200 amperes.

If, due to variations in the contour of the room or area to be covered, the strips of resistance material should be narrowed at any point throughout their length, such as by the occurrence of a column or partition, novel means are provided by the present invention for equalizing the current at such narrowed or interrupted portion of the strip. Referring particularly to Figures 9 and 10 of the drawings, it will be seen that the column 50 causes a gap in the strips 15a and 15b. In order to prevent overheating of the portion 51 of the strip 15b, the transverse margins of the cutaway portion of the strip are provided with conductor clamps or bars 16' which are adapted to be connected by the variable resistance device 55 of suitable construction, which is adapted to be regulated so as to approximate the conductivity of the portion which has been cut out of the strip 15 and so replace this portion and equalize the flow of current through the element 15b. A similar device may, of course, be employed in the gap of the strip 15a caused by the other half of the column 50.

The invention provides a simple method of quickly and inexpensively securing one or more blocks, either of wood, tile, or composition, to a base or support. It is a particularly suitable method for laying floors but is not limited to such use and may be employed in the building up of other structures; and wherever the terms "floor", "flooring", "sub-flooring" or similar expressions are used in the subjoined claims, they are intended to cover all equivalent structures. The binder may, as has been previously pointed out, be placed upon the sub-floor or base as a liquid coating, placed on the screen as a coating at a point remote from the place where the floor is being installed, or may be applied to the boards, blocks, or slabs. In fact, many minor variations of the invention may be made in adapting the same to different operating conditions. The resistance element may be formed in various ways, as the practical man skilled in the art will appreciate.

Having thus described the invention, what is claimed as new and desired to be secured by Letters Patent is:

1. The method of laying sectional flooring upon a base or sub-floor which consists in depositing an adhesive or binding substance on the sub-floor, placing a plurality of blocks or the like upon the binding substance, the blocks being arranged in the positions in which they are to appear in the finished floor, causing a purely physical change in the adhesive or binding substance whereby its chemical composition remains the same, to effect the softening of said substance

so that it intimately contacts with the sub-floor and the bottoms of the blocks, and permitting the binding substance to harden.

2. The method of laying sectional flooring upon a base or sub-floor which consists in depositing an adhesive or binding substance on the sub-floor, which binding substance may be softened upon the application of heat, placing a plurality of blocks or the like upon the binding substance, the blocks being arranged in the positions in which they are to appear in the finished floor, effecting the softening of the adhesive or binding substance by the application of heat so that this substance intimately contacts with the sub-floor and the bottoms of the blocks, and thereafter permitting the binding substance to cool and harden.

3. The method of laying sectional flooring upon a base or sub-floor, which consists in depositing an adhesive or binding substance on the sub-floor together with an electrical resistance appliance, the binding substance being of the type which may be softened by heat, placing a plurality of blocks or the like upon the binding substance, passing an electric current through the resistance appliance to cause the same to evolve heat in sufficient quantity to soften the binding substance, so that this substance intimately contacts with the sub-floor and the bottoms of the blocks, and thereafter interrupting the current flow and permitting the adhesive substance to cool and harden.

4. The method of laying sectional flooring upon a base or sub-floor which consists in applying a coating of adhesive material to the sub-floor, placing a metallic screen upon the coating of adhesive material, superposing a plurality of blocks upon the screen, passing an electric current through the screen to bring about the evolution of heat and the softening of the adhesive substance, so that this substance intimately contacts with the sub-floor and the bottoms of the blocks, and thereafter interrupting the current flow to permit the adhesive substance to cool and harden.

5. The method of laying sectional flooring upon a base or sub-floor which consists in depositing an adhesive or binding substance on the sub-floor together with an electrical resistance appliance, the binding substance being of the type which may be softened by heat, placing a plurality of blocks or the like upon the binding substance, passing an electric current through the resistance appliance to cause the same to evolve heat in sufficient quantity to soften the binding substance, so that this substance intimately contacts with the sub-floor and the bottom surfaces of the blocks, rolling or otherwise exerting pressure upon the upper faces of the blocks while the binding substance is soft, and thereafter interrupting the current flow and permitting the adhesive substance to cool and harden.

6. The method of laying sectional flooring upon a base or sub-floor which consists in depositing an adhesive or binding substance on the sub-floor, placing a plurality of blocks or the like upon the binding substance, the blocks being arranged in the positions in which they are to appear in the finished floor, causing a purely physical change in the adhesive or binding substance whereby its chemical composition remains the same, to effect the softening of said substance so that it intimately contacts with the sub-floor and the bottom surfaces of the blocks, rolling the upper surfaces of the blocks while the binding substance is soft,

and thereafter permitting the binding substance to harden.

7. A floor structure comprising a sub-floor, a metallic screen upon the sub-floor, said screen being of electrical resistance material, a plurality of blocks superposed upon the screen in frictional contact therewith and together forming a floor surface, and a layer of adhesive or binding material intermediate the blocks and the floor and terminal strips firmly secured to the margins of said screen for the attachment of electrical conductors whereby a current of electricity may be passed through said screen for the purpose described.

5 8. The method of securing a block or panel to a base or support which consists in bringing a surface of the block into parallelism with a surface of the support, with a layer of a binding material in dry form between said surfaces, heating the binding material to cause the same to become plastic and to adhere to the mutually facing surfaces of the block and base, and thereafter permitting the binding material to cool and harden.

9. In a construction of the class described, means for securing built-up flooring or like covering material to a sub-floor or other support, comprising a layer of normally solid adhesive or binding substance interposed between said support and said covering material, and a heating element embedded therein, for effecting the softening of said substance in applying or removing said covering material.

10. In a construction of the class described, means for securing built-up flooring or like covering material to a sub-floor or other support, comprising a layer of normally solid asphaltic mastic interposed between said support and said covering material, and an electrical heating element embedded therein, for effecting the softening of said substance in applying or removing said covering material.

11. In a construction of the class described, means for securing built-up flooring or like covering material to a sub-floor or other support, comprising a layer of normally solid asphaltic mastic interposed between said support and said covering material, and a wire mesh comprising an electrical heating element embedded therein, for effecting the softening of said substance in applying or removing said covering material.

12. In a construction of the class described, means for securing built-up flooring or like covering material to a sub-floor or other support, comprising a layer of asphalt having a melting point of approximately 155° F. interposed between said support and said covering material, and a heating element embedded therein, for effecting the softening of said substance in applying or removing said covering material.

13. In a construction of the class described, means for securing built-up flooring or like covering material to a sub-floor or other support, comprising a layer of asphalt having a melting point of approximately 155° F. and a penetration of 40 at 72° F. interposed between said support and said covering material, and a heating element embedded therein, for effecting the softening of

said substance in applying or removing said covering material.

14. In a construction of the class described, means for securing built-up flooring or like covering material to a sub-floor or other support, comprising a layer of normally solid adhesive or binding substance interposed between said support and said covering material, an electrical heating element embedded therein, for effecting the softening of said substance in applying or removing said covering material and terminal strips adapted to make close electrical contact with a margin of said element for attachment to a source of current.

80 15. In a method of removing built-up flooring, as for example, for replacement, said flooring comprising a surface layer bonded to the sub-floor by means of a layer of mastic with which is associated an electrical heating element, the steps of passing an electric current through said heating element, and removing said surface layer when said mastic has softened sufficiently.

95 16. In a built-up floor construction or the like, comprising a sub-floor, a binder layer and a surface layer, a sheet of electrical resistance material associated with said binder layer, a portion of said sheet being cut away, as, for example to accommodate a variation in contour of the building, a variable resistance device adapted to connect the margins of said cut-away portions to bridge the same, whereby the resistance of the adjacent portions of said sheet may be equalized.

100 17. In a method of applying a built-up wall or floor covering, comprising a base, a binder layer, a surface layer, and a sheet of electrical resistance material associated with said binder layer, the step of passing sufficient current through said sheet to heat it to a temperature of approximately 200° F.

110 18. In a method of applying a built-up wall or floor covering, comprising a base, a binder layer, a surface layer, and a sheet of electrical resistance material comprising a three quarter inch mesh screen of 20 gauge wire associated with said binder layer, the step of passing current through said sheet at the rate of 200 amperes per foot of width thereof and one volt per foot of length.

120 19. A floor construction or the like comprising, in combination, a sub-floor or base, a surface layer of flooring, an intermediate layer of normally solid binder material disposed upon said sub-floor, a plurality of sheets of electrical resistance material intimately associated with said binder material for heating and thus softening the same for the purpose described, said surface layer being interrupted adjacent said margins of the sheets of resistance material to provide access to said sheets for connection thereto to a suitable source of current, and removable cover plates bridging the spaces provided by said interruptions in said surface layer of flooring, whereby access may be had to said sheets subsequently to the installation of said floor as for the purpose of softening said binder material for removal of the flooring.

130 135 140 GEORGE L. DRESSER.
